Primary Examiner — Calvin E Vansant*Assistant Examiner* — Mark T. Philipp(74) *Attorney, Agent, or Firm* — Rumit Ranjit Kanakia(57) **CLAIM**

The ornamental design for a car fridge, as shown and described.

DESCRIPTION

FIG. 1 is a front perspective view of a car fridge showing my new design;

FIG. 2 is a rear perspective view thereof;

FIG. 3 is a rear perspective view in another angle thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of FIG. 1;

FIG. 11 is a partial enlarged view of FIG. 2; and,

FIG. 12 is a partial enlarged view of FIG. 2.

The dash-dash broken lines in the figures are for the purposes of illustrating portions of the car fridge, which form no part of the claimed design.

The dash dot dash broken lines on FIGS. 1, 2 and 10-12 are provided to define the enlargement regions in each and form no part of the claimed design.

1 Claim, 10 Drawing Sheets(56)
